ERNEST R. SEWARD, OF KIRKWOOD, MISSOURI, ASSIGNOR TO LEHMANN MACHINE COMPANY, OF ST. LOUIS, MISSOURI, A CORPORATION OF MISSOURI

PIPE-FLANGING MACHINE

Application filed April 18, 1931. Serial No. 531,081.

This invention relates to machines for flanging or otherwise shaping the ends of metal pipe by means of rotatable rollers. The principal object of the present invention is to provide a fluid-operated mechanism for quickly and accurately positioning and feeding the pipe relative to the shaping rollers and to the die and for receiving the thrust of said rollers. Other objects are simplicity and cheapness of construction, fewness of parts, ease of operation and compactness of design. The invention consists in the pipe-shaping machine and in the construction, combinations and arrangements of parts hereinafter described and claimed.

In the accompanying drawings, which form part of this specification and wherein like symbols refer to like parts wherever they occur,

Fig. 1 is a plan view of a portion of a pipe-shaping machine provided with a pipe positioning and feeding means embodying my invention,

Fig. 2 is a vertical transverse cross-section through the pipe clamp on the line 2—2 in Fig. 1; and

Fig. 3 is a longitudinal cross-section through one of the clamp-actuating cylinders.

Referring to the accompanying drawings, my invention is shown in connection with a pipe-shaping machine comprising a bed 1 upon which is mounted a headstock 2 having a horizontally disposed rotary and axially movable spindle 3 mounted therein which extends longitudinally of said bed. Secured to the outer end of the spindle 3 is a face plate 4, upon which is rotatably mounted a pipe-shaping member, preferably in the form of a combined flanging and upsetting roller 5, adapted to engage the end of a pipe 6 located adjacent thereto to form a flange thereon.

Mounted on horizontal slideways 7, which extend longitudinally of the bed 1 on opposite sides thereof, is a die-holding slide 8. The die-holding slide 8 is held against movement along the slideways 7 preferably by means of clamping plates 9 that are bolted to the under sides of said die-holding slide 8 and bear against the under sides of ledges

that extend longitudinally of the bed 1 of the machine on opposite sides thereof. The die-holding slide 8 is provided opposite the face plate 4 of the headstock 2 with a cylindrical opening 8^a adapted to receive and support the forward end portion of the pipe 6 that is to be flanged; and the face-plate opposing end of said opening is countersunk to provide a seat for a suitable die member 10 having a recess therein adapted to receive and shape the portion of the pipe that is forced therein by the rotatable flanging roller 5.

The die-holding slide 8 is further prevented from being moved along the slideways 7 under the thrust of the flanging roller 5 by means of parallel tension rods 12 that extend longitudinally of the machine on opposite sides thereof. Each of the tension rods 12 comprises a forward section which extends through an opening in a laterally extending lug 2^a on the side of the headstock 2 and is threaded to receive a nut 12^a, which bears against the front face of said lug and thus serves as an adjustable stop for preventing rearward sliding movement of said rod. The rear end portion of the forward section of each tension rod 12 extends through an opening provided therefor in the adjacent side of the die-holding slide 8 and terminates in an enlarged head or collar 12^b disposed in abutting relation to a similar enlarged head or collar 12^b on the adjacent forward end of the rear section of said tension rod. The adjacent ends of the forward and rear sections of each tension rod 12 are rigidly secured together and to the die-holding slide 8 by means of a clamping plate 11 that is bolted to said slide and snugly embraces the heads 12^b on the adjacent ends of said sections.

The pipe 6 that is to be shaped is held against rearward sliding movement under pressure of the shaping roller 5 by means of a clamp 13 which is slidably supported on the tension rods 12 to position and feed the pipe relative to said shaping roller and to the die 10. The pipe clamp 13 comprises a main body or cradle portion 14, which spans from tension rod 12 to tension rod 12 and is

provided with openings adapted to receive said rods, and a hinged upper jaw member 15 rotatably mounted at one end on one of said tension rods. The fluid-operated 5 hinged jaw 15 of the pipe clamp is forced down upon the pipe by means of a locking device comprising an arm 16 pivotally supported at 17 between two lugs 18 that extend downwardly from the main body member 14 10 of said clamp beneath the free end of the hinged jaw thereof. The locking arm 16 is pivoted so as to swing vertically and is made long enough to bring the free end thereof above the free end of the hinged jaw 15 when 15 said arm is in an upright position. The free end of the arm 16 has a lever 19 pivotally supported thereon for vertical swinging movement transversely of the pivotal axis of said arm. One arm of said lever is adapted 20 to overhang the free end of the hinged jaw 15 in the closed position thereof and has a roller 20 journaled thereon adapted to bear against the convexly curved upper cam surface 21 of the free end portion of said jaw, whereby 25 said roller when swung inwardly over the cam surface of the jaw will operate to force the same downwardly into engagement with the pipe. The other arm of the roller supporting lever 19 is provided with an adjusting 30 screw 22, which abuts against the supporting arm 16 and serves as an adjustable stop for adjusting the position of the roller 20 relative to the cam surface on the hinged 35 jaw of the clamp.

35 The hinged jaw member 15 of the pipe clamp is opened and closed preferably by means of a piston 26 working in a cylinder 24 pivotally supported at 25 in the lower or main body member 14 of said pipe clamp.

40 The upper end of the rod 26 of the piston is pivotally connected at 27 to lugs 28 that project from the hinged end of the jaw 15 of the pipe clamp. The arm 16 is actuated by means of a fluid-operated piston 29, which 45 works in a cylinder 30 pivotally supported at 31 between the lugs 18 on the lower member 14 of the pipe clamp and is pivotally connected at 31 with said arm by means of a piston rod 32.

50 The pipe clamp 13 is slid longitudinally of the tension rods 12 to position and feed the pipe relative to the shaping roller 5 and to the die 10 by fluid-operated means comprising a cylinder 33 and piston 34 mounted on 55 each of said tension rods. As shown in Fig. 3 of the drawings, each cylinder 33 surrounds one of the tension rods 12 and is provided at its forward end with a portion of reduced diameter that is threaded or otherwise rigidly secured within the tension rod receiving opening in the adjacent end of the lower or main body member 14 of the pipe clamp 13. The piston 34 is a fixed piston that is pinned or otherwise rigidly secured to the tension 60 rod; and said piston is provided with suit-

able packing rings 35 for preventing leakage between the piston and cylinder.

A motive fluid under pressure, preferably an incompressible fluid such as oil, from a suitable source is admitted to and released 70 from the forward and rear ends of each cylinder 33 through pipes 36 and 37, respectively, for effecting a relatively reciprocating motion between the cylinder and piston members. The pipes 36 and 37 are connected 75 by a branch pipe 38 having a two-way valve 39 therein at its point of connection with the pipe 36. The pipes 36 and 37 are further connected by a second branch pipe 40, which communicates with the pipe 36 forward of the branch pipe 38 and with the pipe 37 80 rearward of said branch pipe 38. The branch pipe 40 is provided at its point of connection with the pipe 37 with a two-way valve 41. With this arrangement, when it is 85 desired to move the pipe in the pipe clamp 13 in the direction of the shaping roller 5, the valves 39 and 41 are manipulated to permit the oil to flow through the pipe 37, branch 90 pipe 38, valve 39 and pipe 36, to the forward ends 95 of the two cylinders 33, thereby imparting a forward sliding movement to said cylinders and the pipe clamp 13 carried thereby. During such forward movement of the cylinders 33 the excess oil in the rear portions 99 thereof is permitted to flow therefrom through the pipe 37, valve 41, branch pipe 40 and again into the pipe 36. When a rearward movement of the pipe clamp 13 is desired, the valves 39 and 41 are manipulated 100 so as to permit the oil to be forced into the rear end portions of the two cylinders 33 and thus cause said cylinders, together with the pipe clamp carried thereby, to slide rearwardly along the tension rods 12. The 105 course of the oil during such movement is through the pipe 37 to the rear ends of the cylinders and from the forward ends of the cylinders through the pipe 36. By this arrangement, the pipe clamp 13 may be readily shifted along the tension rods in either direction to quickly and accurately position and feed the pipe relative to the shaping roller 5 and to the die 10, while the oil, which 110 is incompressible, serves to prevent rearward 115 sliding movement of the cylinders under the thrust of said shaping roller.

Obviously, the hereinbefore described arrangement admits of considerable modification without departing from the invention. 120 Therefore, I do not wish to be limited to the precise arrangement shown and described.

What I claim is:

1. A pipe-shaping machine comprising 125 means for shaping the pipe, said means including a die member adapted to receive a portion of said pipe, a pipe support mounted for horizontal sliding movement towards and away from said die member, means for securing said pipe to said support for move- 130

ment therewith in either direction of its sliding movement, and fluid-operated means for moving said pipe support in either direction of its sliding movement.

5 2. A pipe-shaping machine comprising means for shaping the pipe, said means including a die member adapted to receive a portion of said pipe, a pipe clamp slideable towards and away from said die member, and fluid-operated means for moving said pipe clamp in either direction of its sliding movement.

10 3. A pipe-shaping machine comprising means for shaping the pipe, a pipe support movable relative to said shaping means, fluid-operated means for moving said pipe support, said fluid-operated means comprising cooperating piston and cylinder members, one of said members being operatively connected to said pipe support to actuate the same, and means for supplying motive fluid to the opposite ends of said cylinder to effect a relatively reciprocating motion between the cylinder and the piston members.

15 4. A pipe-shaping machine comprising means for shaping the pipe, a pipe clamp slideable towards and away from said shaping means, and fluid-operated means for sliding said pipe clamp, said fluid-operated means comprising a cylinder secured to said pipe clamp, a fixed piston in said cylinder, and means for supplying motive fluid to said cylinder on opposite sides of said fixed piston.

20 5. A pipe-shaping machine comprising means for shaping the pipe, a pipe clamp movable relative to said shaping means, fluid-operated means for opening and closing said pipe clamp, fluid-operated means for locking said pipe clamp in closed position, and fluid-operated means for moving said pipe clamp relative to said pipe-shaping means.

25 6. A pipe-shaping machine comprising means for shaping the pipe, a pipe clamp movable relative to said shaping means, fluid-operated means for opening and closing said pipe clamp, fluid-operated means for locking said pipe clamp in closed position, and fluid-operated means for moving said pipe clamp relative to said pipe-shaping means and for preventing movement of the pipe clamp due to the thrust of the pipe-shaping means on the pipe therein.

30 7. A pipe-shaping machine comprising means for shaping the pipe, horizontally disposed tension rods secured to said machine, a pipe clamp slideable upon said tension rods towards and away from said pipe-shaping means, and fluid-operated means for moving said pipe clamp along said tension rods, said fluid-operated means comprising a cylinder slideable longitudinally of each of said tension rods and fixed to said pipe clamp,

and a piston mounted in said cylinder and fixed to the tension rod.

8. A pipe-shaping machine comprising means for shaping the pipe, horizontally disposed tension rods secured to said machine, a pipe clamp slideable upon said tension rods towards and away from said pipe-shaping means, fluid-operated means for moving said pipe clamp along said tension rods and for preventing movement of said pipe clamp due to the thrust of the pipe-shaping means, said fluid-operated means comprising a cylinder 70 slideably mounted on each of said tension rods, a piston located in said cylinder and fixed to the tension rod, and means for supplying 75 a motive fluid to the opposite ends of said cylinder.

9. A pipe-shaping machine comprising means for shaping the pipe, a pipe clamp mounted for sliding movement towards and away from said pipe-shaping means, said pipe clamp being provided with a hinged jaw member, fluid-operated means carried by said pipe clamp for opening and closing 80 said hinged jaw member, and fluid-operated means for locking said hinged jaw in closed 85 position.

10. A pipe-shaping machine comprising means for shaping the pipe, a pipe clamp mounted for sliding movement towards and away from said pipe-shaping means, said pipe clamp being provided with a hinged jaw member, fluid-operated means carried by 90 said pipe clamp for opening and closing said hinged jaw member, fluid-operated means 95 for locking said hinged jaw member in closed position, said fluid-operated locking means comprising an arm pivotally secured to said pipe clamp, and means on the free end of said arm adapted to bear against the free 100 end of the closed jaw for forcing the same into engagement with the pipe.

11. A pipe-shaping machine comprising means for shaping the pipe, a pipe clamp mounted for sliding movement towards and away from said pipe-shaping means, said pipe clamp being provided with a hinged section, fluid-operated means carried by said pipe clamp for opening and closing the hinged section thereof, fluid-operated means 110 for locking said hinged section in closed position, said fluid-operated locking means comprising an arm pivotally secured to said pipe clamp, and a roller rotatably supported on the free end of said arm and adapted to 115 bear against the free end of said hinged section in the closed position thereof.

12. A pipe-shaping machine comprising means for shaping the pipe, a pipe clamp mounted for sliding movement towards and away from said pipe-shaping means, said pipe clamp being provided with a hinged section, fluid-operated means carried by said pipe clamp for opening and closing the hinged section thereof, fluid-operated means 125 130

for locking said hinged section in closed position, said fluid-operated locking means comprising an arm pivotally secured to said pipe clamp, a roller rotatably supported on the free end of said arm and adapted to bear against the free end of said hinged section in the closed position thereof, and means for adjusting said roller relative to said arm.

Signed at St. Louis, Missouri, this 11th
10 day of April, 1931.
